TELEGRAPHY-PRACTICING DEVICE

Portis P. Shaw, Exeter, Calif.

Application February 2, 1944, Serial No. 520,803

2 Claims. (Cl. 35—14)

The invention aims to provide an exceptionally simple and inexpensive, yet an efficient device for practicing telegraphy, either when learning or after becoming adept, to keep in practice.

With the foregoing in view, the invention resides in the novel structure hereinafter described and claimed, description being accomplished by reference to the accompanying drawing.

Figure 1 is a side elevation partly broken away and in section.

Figure 2 is a top plan view.

Figure 3 is a transverse sectional view on line 3—3 of Fig. 1.

A preferred construction has been illustrated in the drawing and will be specifically described, with the understanding, however, that within the scope of the invention as claimed, minor variations may be made.

A base 5 is provided, said base being preferably formed from wood or plastic. Front and rear anvils 6 and 7 are rigidly carried by the base 5 and are upwardly exposed, said anvils being preferably formed by ordinary tacks driven downwardly into said base.

Projecting upwardly from and rigidly secured to the base 5, between the front and rear anvils 6 and 7, are two laterally spaced posts 8, and a horizontally elongated lever 9 extends between these posts and is fulcrumed thereon. This lever is preferably formed from wood or plastic and it may be fulcrumed by providing it with a through-pin 10 having pointed ends 11 engaging similarly shaped recesses in two wood or metal screws 12 threaded through the posts 8. These posts are preferably of wood or plastic with their lower ends suitably secured in sockets 13 in the base 5.

The lever 9 carries downwardly exposed front and rear hammers 14 and 15 for cooperation with the front and rear anvils 6 and 7 respectively. The hammer 14 is preferably formed by the lower end of a metal rod 16 which is threaded through the front end of the lever 9 and through upper and lower nuts 17 and 18, the nut 18 being preferably embedded in the lower side of the lever 9 while the nut 17 is simply a lock nut which can be readily loosened when it is desired to vertically adjust the rod 16 to vary the distance between it and the front anvil 6. The upper end of this rod 16 carries a finger knob 19 for use in tilting the lever 9 in a direction to bring the front hammer 14 against the front anvil 6, and to tilt said lever 9 in the opposite direction, a spring 20 is provided. The upper end of this spring is suitably connected with

the lower end of a thumb screw 21 which is threaded through the lever 9 and through a nut 22 embedded in the lower side of said lever, and the lower end of said spring is seated in a socket 23 formed in the base 5. By adjusting the tension of the spring 20 by means of the thumb screw 21 and vertically adjusting the screw 16, the device may be readily adjusted to the touch of the person who is to use the same.

As the lever 9 is oscillated under the influence of finger pressure and the spring 20, the hammers 14 and 15 strike the anvils 6 and 7 and produce a clicking sound which readily simulates that produced by an ordinary sending key. Thus, regardless of the simplicity and inexpensive nature of the invention, it may be advantageously used in practicing telegraphy, whether the Morse code or some other code be used.

I claim:

20. 1. A telegraphy practicing device comprising an elongated horizontal wooden base having two laterally spaced upwardly open sockets between its ends and a third upwardly open socket spaced forwardly from said two sockets, two parallel wooden posts having their lower ends secured in said two sockets, aligned bearing screws threaded through the upper ends of said posts, said screws having bearing sockets in their inner ends, a wooden lever above said wooden base and extending between said wooden posts, said wooden lever having an integral downwardly projecting portion at its rear end, a fulcrum pin extending through said lever and having pointed ends rockably received in said bearing sockets, front and rear metal tacks driven downwardly into said base under the front and rear ends of said wooden lever respectively, a third metal tack driven upwardly into said downwardly projecting portion of said lever to strike said rear tack, a metal screw extending vertically through the front end of said wooden lever and having a lever-operating and screw-adjusting knob at its upper end, the lower end of said metal screw being positioned to strike said front tack, upper and lower nuts threaded on said screw, said lower nut being embedded in the lower edge of said wooden lever, said upper nut being a lock nut and abutting the upper edge of said wooden lever, a metal spring seated in said third socket 50 of said base, an adjusting screw extending vertically through said wooden lever and having its lower end engaged with the upper end of said spring, and a nut threaded on said adjusting screw and embedded in the lower edge of said wooden lever.

2. A telegraphy practicing device comprising a base having front and rear anvils, a lever fulcrumed between its ends above said base, said lever having a rear hammer positioned to strike said rear anvil, a vertical screw extending through the front end of said lever and having its lower end positioned to strike said front anvil,

the upper end of said screw having a lever-operating and screw-adjusting knob, means for locking said screw after adjustment, and a spring for rocking said lever in a direction to depress its rear end.

PORIS P. SHAW.
